Patented Aug. 26, 1913.

UNITED STATES PATENT OFFICE.

JOSEPH F. McPARLAND, OF DUBUQUE, IOWA.

DRAIN-HEAD.

1,071,253.

Specification of Letters Patent. Patented Aug. 26, 1913.

Application filed February 18, 1913. Serial No. 749,231.

To all whom it may concern:

Be it known that I, JOSEPH F. McPARLAND, a citizen of the United States, residing at Dubuque, in the county of Dubuque 5 and State of Iowa, have invented certain new and useful Improvements in Drain-Heads; and I do hereby declare the following to be a full, clear, and exact description of the invention, such as will enable others skilled in the art to which it appertains to make and use the same.

This invention relates to drain-heads.

An object of the invention is to provide an improved form of drain head to be used 15 in connection with tile or other drain pipe for conveying the water from the clay-soils downward through the stratum of clay into the sub-strata of sand or other soil which is more porous than the clay, so as to provide 20 a proper drainage for the clay-soil.

Another object of the invention is to provide a device of this character in connection with a comparatively shallow well of considerable area, and to cover said well so as to to 25 prevent the same from being filled with earth, so that water may accumulate within the well whence it is conducted downward through the drain pipe or tile.

A further object of the invention is to 30 provide a drain-head of this character with an air outlet and with a protecting cap or crown for the air outlet.

Other objects and advantages may be recited hereinafter and in the claims.

35 In the accompanying drawings which supplement this specification, Figure 1 is a vertical sectional view through my improved drain-head and through the well and drain tile associated therewith. Fig. 2 is a perspective view of my improved drain-head and the tile associated therewith, and, Fig. 3 is a fragmental sectional view of the drain head and cap taken on the line 3—3 of Fig. 1.

40 Referring specifically to the drawings, in 45 which similar reference characters indicate the same parts in all of the figures, 6 indicates a hollow cap member and 5, a separate dome shaped crown member. The crown member 5 is provided with a horizontal peripheral flange 10 and has its central upper portion on the inside thickened, at 15, and flattened to rest upon the top of a shaft 8, preferably composed of superposed tiles. Upwardly projecting from the center of the 50 crown member is a tubular extension 12 having a central bore 11, which communicates

with the interior of the cap member 6. The cap member rests upon the top of the crown member and is provided in its lower edge with openings 13. The thickened portion 15 of the crown member is provided with radial grooves 14 which communicate between the interior of the crown member and the interior of the shaft 8, the latter communicating in any suitable manner at its lower end with the surrounding earth.

To fix the device in position for operation, a proper shallow well 7 is dug into the clay stratum and in its center is bored a deeper circular opening to receive the lower end of 70 the shaft 8, said opening extending into the more porous earth below the clay stratum. The upper edge 9 of the well forms a shelf upon which the flange 10 of the crown is placed, after which the cap 6 is placed upon 75 the top of the crown, the spaces between the top of the tubular extension 12 and the interior of the cap affording free communication between these two parts. Water in the clay stratum will settle into the well and 80 up under the crown, and will pass through the grooves 14 into the center of the shaft, down which it drops and from the lower end of which it percolates or soaks into the porous earth below. Air in the dome will be 85 forced upward and passing through the grooves 14 will rise through the tubular extension 12, passing over the top thereof into the cap, and from the cap out through the openings 13.

90 It will be seen that I have provided an improved form of drain head which is fully capable of attaining the foregoing objects in a thoroughly practical and efficient manner.

I do not limit my invention to the exact details of construction, combination and arrangement of parts as herewith illustrated and described, but my invention may only be limited by a reasonable interpretation of the claims.

100 I claim:

1. A drain head consisting of a dome-shaped cap having a horizontal peripheral base flange around the bottom edge thereof and a central vertical tubular extension at its top, and an inverted cup-shaped crown seated over the tubular element, communicating with the interior of the cap and provided with air outlets below the top of the tubular element.

105 2. In combination, a drain shaft centrally erected in a well, a cap resting upon the top

of the drain pipe and the edge of the well and having a central opening communicating with the drain shaft, the relation of the cap and shaft being such as to provide openings for establishing communication between the shaft and well, and a crown over the central opening provided with air outlets.

3. A drain head consisting of a dome-shaped cover for a well, having an aperture

through its top, and a substantially hemispherical crown over the aperture of the cover, said crown having air outlets.

In testimony whereof I have signed my name to this specification in the presence of two subscribing witnesses.

JOSEPH F. McPARLAND.

Witnesses:

G. A. CROWSHAW,

T. J. FITZPATRICK.
